UNITED STATES PATENT OFFICE.

REBECCA GRAVES, OF SPOKANE, WASHINGTON.

BATH SUPPORT.

Application filed December 15, 1922. Serial No. 607,223.

To all whom it may concern:

Be it known that I, REBECCA GRAVES, a citizen of the United States, residing at Spokane, in Spokane County, and State of Washington, have invented certain new and useful Improvements in Bath Supports, of which the following is a specification.

My present invention relates to improvements in bath supports which, while not designed for exclusive use in bathing infants or children, is especially adapted for this purpose. The primary object of the invention is the provision of a bath appliance in which the person may be supported within the bath tub with the support or appliance partially submerged in the water contained in the tub, or the support may be suspended above the water line in the tub. This support is of flexible material and fashioned in such manner as to be suspended from the opposite top edges of the bath tub and form a partial enclosure for the protection and support of the infant. Adjustable suspending means are employed which may be manipulated for the purpose of changing the conformation or shape of the support and thus adapt it to accommodate the child or infant in various positions. By manipulating the adjustable suspending devices the shape of different portions of the flexible support may be changed, one portion may be elevated above another portion, and those portions forming the side walls of the support may be given a selected depth. In this manner the head portion of the support may be elevated, while the foot portion is permitted to sag and form a pocket of greater depth than the head portion for the accommodation of an infant in a reclining position, or the different portions of the support may be adjusted to position to support the infant in a sitting posture.

These different formations and adjustments of the shape of the support are possible because of the specific construction of the flexible support, and its adjustable suspending means, as will be hereinafter more fully pointed out and claimed.

In the accompanying drawings I have illustrated one complete example of the physical embodiment of my invention wherein the parts are fashioned and combined according to one mode I have thus far devised for the practical application of the principles of my invention.

Figure 1 is a top plan view showing the

device of the invention supported within a bath tub, in position for use.

Figure 2 is a vertical, longitudinal sectional view at line 2—2 of Figure 1.

Figure 3 is an enlarged detail view of the foot portion of the flexible support showing a portion of a screen for a drain opening, and also illustrating a pair of laced plackets in the body of the support whereby an enlarged, deeper portion or pocket may be formed at the foot of the support.

Figure 4 is an enlarged detail sectional view of a portion of the tub illustrating one of the suspending hooks and suspending or adjusting buckle.

In order that the invention and its utility may be readily understood I have illustrated a conventional form of bath tub 1 having the usual curled or curved top edges 2.

The bath support, as a whole is designated by the numeral 3, and is made up or fashioned from suitable textile fabric, or other flexible material suitable for the purpose, which may or may not be waterproof, as desired, but is preferably of approximate rectangular form. The ends of the support are designated as the head portion 4 and foot portion 5, and it is intended that the infant when being bathed, shall be placed in the support, as for instance to lie with its head in the head portion 4 at the left end in Figures 1 and 2 and its feet in the foot portion 5 at the right end of the support.

Reinforcing edge strips or binding tapes 6 are secured around the edges of the support, and at suitable intervals along the opposite parallel edges of the support are attached suspending straps 7. In Figure 1 it will be seen that the straps are arranged in pairs at opposite edges of the support in order that they may co-operate in supporting the device in adjusted position. Each suspending strap is provided with an adjusting buckle 8 for lengthening or shortening the suspending strap, and a suspending hook 9 is attached at the end of each strap and adapted to engage over the curled edge of the tub, as seen in Figure 4.

The support is suspended within the tub by means of these suspending devices, and it will be apparent that by adjusting the length of the straps, various forms or shapes may be imparted to the support. For instance when the child is lying in the support, it is important that its head be properly supported, and by relatively shorten-

ing the pair of straps 7' in Figure 1 a ridge 8', extending transversely of the support, is formed at its inner or upper side, to accommodate the back of the neck of the child, 5 and properly support the body and head of the recumbent child. The straps toward the right end or foot portion of the support may be lengthened with relation to the straps at the left end or head portion of the support 10 to permit the foot portion to sag below the head portion, as indicated in Figure 2. In this position, not only is better accommodation provided for the infant, but water accumulating in the support may readily run 15 down the bottom of the support and drain through a gauze or perforate screen 10 in the bottom of the support. This drain screen may be of porous fabric or other suitable material and is inserted in an opening 20 provided therefor in the support with its edges securely stitched to the support for retention therein.

The foot portion 5 of the support is provided with a pair of plackets 11 and 12, 25 spaced apart as shown and extending outwardly from the drain opening in the bottom of the support to the edge of the support. The plackets radiate from the longitudinal center of the support, on diagonal lines, 30 and their edges are provided with binding tapes 13 having eyelets or eyes 14 for the lacing strings 15.

The plackets are closed or filled with V-shape pieces or darts 16 folded or pleated on 35 converging lines complementary to the edges of the plackets, as seen in Figure 1, while in Figure 3 the lacing strings 15 appear on the under or outer sides of these pleats. It will be obvious that the lacings strings may 40 be used as draw strings to close the plackets and fold the pleated portions 16 to reduce the circumferential area of the foot portion or end of the support and fashion this end of the support as a pocket to prevent a child 45 from falling out at this end. The suspending straps at the foot portion of the support are also adjustable for the purpose of lowering or elevating the foot portion of the support, as desired.

50 In the position of the support indicated in Figure 2 it is adapted to accommodate an infant in the same manner that the infant lies in the mother's lap or is held in the mother's arms, for bathing. The ridge 8' formed

transversely of the support by drawing on 55 the straps 7' fits neatly under the infant's neck and the head is supported in the head portion 4, to take the weight off the child's neck. As the child grows stronger and is enabled to more nearly support itself, the 60 relative positions of the head and foot portions of the support are changed, the former being elevated with relation to the latter, to accommodate the child, and form a protective support. 65

The size of the support is of course varied, and larger supports are adapted for adults to be used in hospitals for the accommodation of patients, or in the home for the benefit of invalids requiring personal attention. 70

It will be apparent that the support may be maintained in a sanitary condition by laundering and may be quickly and readily dried after use. It may with facility be suspended from the sides of the bath tub, or 75 suspended from other suitable support when required, and with equal convenience the hooks may be disengaged from the tub sides and the support removed when not required for use. 80

Having thus fully described my invention, what I claim as new and desire to secure by Letters Patent is:—

1. A bath support of flexible material having separately adjustable suspending 85 means attached at opposite edges thereof and arranged in pairs, said support having a foot portion formed with a drain, and plackets extending from its center to its edge, pleats in said plackets, and means for 90 closing or partially closing said plackets.

2. A bath support of flexible material having suspending means, said support having plackets radiating from its longitudinal center to its edge, pleats in said plackets, and 95 a lacing string in said plackets.

3. A bath support of flexible material having separately adjustable suspending means attached at opposite edges and arranged in pairs, a perforate piece set in the 100 bottom of said support as a drain, plackets radiating from said drain to the edge of the support and provided with eyelets, lacing strings in the eyelets, and pleats secured in said plackets. 105

In testimony whereof I affix my signature.

REBECCA GRAVES.
